SHIFTING AND SKIDDING DEVICE FOR USE
WITH HOISTING JACKS AND THE
METHOD OF USING IT

Edward O. Keator, Dayton, Ohio

Application April 12, 1938, Serial No. 201,630

16 Claims. (Cl. 254—133)

This invention relates to the shifting of railway tracks, the present application being a continuation in-part of my prior application for Shifting and skidding devices for use with hoisting jack and the method of using them, filed March 13, 1931, Serial No. 522,456, and renewed July 3, 1936.

One object of the invention is the provision of jacking apparatus for shifting railway tracks which enables a track to be moved a distance considerably greater than the lift of the jack with a single setting of the foot of the jack.

Another object of the invention resides in the method of shifting a track in which material is placed at the side of the track and the track jacked laterally so as to shift the track rails and the ties to move and spread the material that has been placed at the side of the track.

Another object of the invention is to spread and level off by means of the track itself the material on which the track is being shifted, to raise or lower the track to conform to predetermined grades, and to surface the track to take out vertical dips and rises, all being accomplished concurrently and simultaneously with shifting, and without the assistance of any of the usual picks, shovels, bars, spreader machines or track machines.

Other objects and advantages of the invention will be apparent from the following description, the appended claims, and the accompanying drawings.

In accordance with the present invention, excavated material such as earth and rocks which is to be disposed of is carried on cars over a railroad track and is dumped alongside of the track at the point of disposal to create or augment a fill. As the dirt is dumped the rocks and heavy, larger portions will naturally gravitate down to the bottom of the mound that is formed at the side of the track, while the smaller pieces remain near the top of the mound. When a certain amount of material has been dumped at the side of the track the track is shifted bodily in the direction in which the fill is being constructed and the material is thereby leveled by jacking the rail of the track which is adjacent the mound so as to shift the track rails and the ties in a substantially horizontal direction and thus move the upper portion of the dumped material along while moving the track over onto the lower portion of the material dumped. The track is shifted before there is a broad expanse of fill at the side of the track so that there will not be an unusually large amount of material

to be pushed ahead of the track as the track is jacked along laterally.

In the drawings, in which the apparatus and the method of operation are illustrated,

Fig. 1 illustrates a fixture to be clamped to one of the rails of a track and which serves as an abutment for a jack;

Fig. 2 is an elevational view of a track jack such as might be used;

Figs. 3 and 4, respectively illustrate the beginning and ending of the first shift of the track;

Fig. 5 shows the completion of the second or subsequent shifting step, with the foot of the jack in the same place it occupied in the shifting step illustrated in Figs. 3 and 4; and

Fig. 6 illustrates a third or later step in the movement of the track, the foot of the jack still being in the same position.

Referring more particularly to the drawings, the fixture which is adapted to be clamped to one of the rails of the track to serve as a jack abutment comprises two principal parts indicated respectively at A and B. The part A comprises horizontally extending members 6—6, the upper edges of which are adapted to bear against the underside of the base of a rail. These members are united by a web 7. An upwardly extending member 5 has a lip 13 adapted to hook over the edge of the base of the rail as indicated in Figs. 3 to 6. The part B has horizontal members 12—12 adapted to bear against the under side of the base of the rail, opposite the part A, and also has an upwardly extending member 9 that carries a lip 13' which hooks over the edge of the rail base as shown in Figs. 3 to 6. These parts, A and B, are united by a bolt 8 that passes through the web 7 and through the member 9, the nut 10 engaging the bolt and tightly clamping the two parts to the rail. Extending substantially horizontally from the part A is an arm 3, the end of which is provided with a seat or abutment 1 flanked by lugs 2. The seat 1 is intended as the abutment for a jack, and the lugs 2 serve to prevent the jack from slipping off the seat in case the jack is improperly set.

As shown in Fig. 4, the jack is provided with a rack 19 that can be extended step by step in the body or housing 16, by means of the lever 18. The rack may be tripped and retracted into the housing. At its lower end the rack 19 carries a laterally projecting shoe 15, and at its upper end it carries a head 17. Either the shoe or the head can be used in the jacking operation, and in Fig. 4 the rack is illustrated as fully extended,

the positions of the shoe and head when the rack is retracted being indicated by dotted lines. The stroke of the rack is limited by the slot 14, see Fig. 2, in which the shoe 15, attached to the 5 rack, moves. Usually the stroke of the rack is about equal to a little more than half of the length of the rack.

Fig. 3 shows the start of the first step in shifting the track. The jack is set in an inclined 10 position with the shoe 15 against the abutment 1 and the foot of the jack on the ground. The lever 18 is then operated to extend the jack until the 15 rack has completed its stroke, thus shifting the track to the position it occupies in Fig. 4. In this movement of the track, the dirt that has 20 been dumped at the side of the track is pushed along by the ends of the ties and by the rail itself, the jacking pressure serving to move the ties in the general direction of their length or 25 at a suitable angle to the horizontal where it is desired to surface the track;—that is eliminate the dips and rises at the same time the track is shifted and by the same operation elevate the rail to which the jacking pressure is applied. 30 25 Setting the jack in an oblique position imparts to the track a tilting lift to allow the material of the fill to flow under the ties and thus compensate for subsequent settling of the material so that the desired elevation of the track may be secured and eliminating the need for subsequently tamping material under the ties or subsequently surfacing the track.

The length of the extension 3 of the fixture 35 A—B is made such that having shifted the track to the position shown in Fig. 4, retraction of the rack will bring its head far enough back to permit the head to drop behind the head 20 of the rail, the foot of the jack remaining where it was when the first shift of the track was effected. 40 Then by again operating the lever 18 the track can be shifted a second stage. Only one or two jacks are required for the track shifting operation for shifting an entire line of track. Preferably two jacks are employed simultaneously, 45 spaced apart a distance of ten to twenty feet along the rail being jacked. Obviously this is a simple operation and is effected with very little labor. Not only is it unnecessary to find a new footing for the jack, but the labor of fixing the 50 jack up and resetting it is eliminated, and the ground under the jack having been compacted by the first shift will not compress much further during the second shift. After compression of the second shift, retraction of the rack brings the 55 head 17 back far enough so that it can drop behind the abutment 1 so that the jack, with the same footing, can be used to shift the track a third step.

It will be noticed that each successive shift 60 of the track is made with the jack less inclined so that the track tilting effect becomes less with each shift.

In carrying out the method it is preferred that 65 only enough material be dumped at the side of the track so that with but three shifts with a common jack base setting the track can catch up with the fill, and the ends of the ties will then be adjacent the edge of the fill. More material is then dumped at the side of the track and the fill 70 built up and the track shifted onto the new fill as before.

Referring to Fig. 1 it will be noted that the 75 part B of the fixture A—B carries a plate 11. This plate 11 is of sufficient size to almost reach the distance between adjacent ties, and serves to push

material from between the ties at the jack location as the track is shifted, maintaining this space between the ties more or less unobstructed and pushing the dirt ahead of it as the track is shifted so that the jack can be set for shifting 5 without digging a hole for it. Furthermore with a fixture A—B at the location of each tie space along the length of the track the entire track can be kept substantially on top of the fill and the shifting made easier. 10

As the rails may not be always shaped like the rail shown, the abutment for the jack head 17 may be provided on the part A, which as shown is provided with a flange or lug 4 extending substantially horizontally from the vertical member 15 5. This flange can thus be used for an abutment in lieu of the rail head 20, and in moving the track the jack may be set so that in the first shift the shoe 15 of the jack bears on the abutment 1, and in the second shift the head 17 of 20 the jack may bear against the second abutment 4. In the third shift the head 17 may bear on the abutments 1 and 4, or between the abutment 1 and the track, is preferably a little less than the stroke 25 of the rack so that after the rack has been shifted one stroke and the rack has been lowered there will be a clearance between the head 17 of the rack and the abutment 4. This clearance is provided since the track may spring back slightly 30 after the rack is tripped at the end of a movement, and to facilitate the dropping of the head 17 behind the abutment 4 after the first shift. In practice about an inch or possibly two inches 35 of clearance may be provided for. That is, the distance from the abutment 1 to the abutment 4 may be one or two inches less than the stroke of the track.

Where the rail is used as the second abutment for the jack, the fixture A may be dispensed 40 with, this part being illustrated in the drawings although it is not always necessary to use it.

While the method herein described, and the form of apparatus for carrying this method into effect, constitute preferred embodiments of the 45 invention, it is to be understood that the invention is not limited to this precise method and form of apparatus, and that changes may be made in either without departing from the scope 50 of the invention which is defined in the appended claims.

What is claimed is:

1. Apparatus for shifting a railroad track laterally, comprising a jack having a movable rack carrying a head and a shoe, a fixture to attach 55 to a rail of said track, comprising a member extending laterally with reference to said rail, the end of said extension serving as an abutment against which the shoe is adapted to bear, the distance from said abutment to the rail being 60 such that, with a single setting of the foot of the jack, when the rack has been extended to its limit with the shoe bearing on said abutment, retraction of the rack will bring it into such 65 position, longitudinally, that its head can engage the rail, to the end that a second extension of the rack will move the track a second stage.

2. Apparatus for shifting a railroad track laterally, comprising a jack having a movable rack 70 carrying a head and a shoe, a fixture to attach to a rail of such track, comprising a member extending laterally with reference to the rail, the end of said extension serving as an abutment against which the shoe is adapted to bear, the 75

distance from said abutment to the rail being such that, with a single setting of the foot of the jack, when the rack has been extended to its limit with the shoe bearing on said abutment, retraction of the rack will bring it into such position, longitudinally, that its head can engage the rail, to the end that a second extension of the rack will move the track a second stage, said fixture carrying a scraper whereby material between the ties is pushed out of the space.

3. Apparatus for shifting a railroad track laterally, comprising a jack having a movable rack carrying a head and a shoe, a fixture to attach to a rail of said track, comprising a member extending laterally with reference to the track, the end of which extension serves as an abutment against which said head or shoe are adapted to bear, the length of such projection being such that the distance from said abutment to the rail is equal to the stroke of the rack minus whatever is allowed for clearance, to the end that, with a single setting of the foot of the jack, when the track has been moved a distance equal to the stroke of the rack, with the shoe bearing on said abutment, retraction of the rack will bring said head into such position, longitudinally, that it can engage the rail, so that when the rack is again extended it will move the track a second distance, so that when the rack is retracted a second time the head will be in such position, longitudinally, that it can engage said abutment, and move the track a third distance.

4. The method of moving an object with a jack having a foot, and having a movable rack carrying a shoe and a head, which method comprises providing the object with two abutments, the distance between which is equal to the stroke of said rack minus whatever is allowed for clearance, moving said object through the range of the jack with said shoe bearing on the first abutment, retracting the rack and then moving it a second stage with the head of the rack bearing on the second abutment, the foot of the jack resting on the same footing during both moves.

5. The method of moving an object with a jack having a head, a shoe and a foot, which method comprises providing the object with two abutments, the distance between which is equal to the stroke of the rack minus whatever is allowed for clearance, moving said object through the range of the jack with said shoe bearing on the first abutment, then retracting the rack and moving it a second stage with the head of the rack bearing on the second abutment, again retracting the rack and moving the object a third stage with the head of the rack bearing on the first abutment, the foot of the jack resting on the same footing during all of said moves.

6. The method of moving a track laterally with a jack having a foot, and having a movable rack carrying a head and a shoe, which method comprises providing the track with an abutment removed from the track a distance equal to the stroke of the rack minus whatever is allowed for clearance, moving the track with the shoe bearing on said abutment, then retracting the rack and moving the track a second stage with the head bearing on the track, the base of the jack bearing on the same footing during all of said movements.

7. The method of moving a track laterally with a jack having a foot, and having a movable rack carrying a head and a shoe, which method comprises providing the track with an abutment removed from the track a distance equal to

the stroke of the rack minus whatever is allowed for clearance, moving the track with the shoe bearing on said abutment, then retracting the rack and moving the track a second stage with the head bearing on the track, then retracting the rack again and moving it a third stage with the head of the rack bearing on the abutment, the base of the jack bearing on the same footing during each of said movements.

8. A fixture adapted to be secured to a rail, having an extension projecting perpendicularly with reference to the rail, the end of said extension being adapted to serve as an abutment for the head or the shoe of a jack set perpendicularly with reference to the track, whereby to shift the track laterally, said extension carrying a lug adapted to serve as a second abutment, to be used with the jack still perpendicular to the track, the distance from the first abutment to the second, in a line perpendicular to the track, being equal to the stroke of the rack of the jack minus whatever is allowed for clearance.

9. In combination, a jack having a lifting bar provided with a shoe adjacent its lower end and a head adjacent its upper end, and a fixture adapted to be secured to a rail, having an extension projecting perpendicularly with reference to the rail, the end of said extension adapted to serve as an abutment for the head or the shoe of a jack set perpendicularly with reference to the track, whereby to shift the track laterally, said extension having a lug adapted to serve as a second abutment to be used with the jack still perpendicular to the track, the distance from the first abutment to the second, in a line perpendicular to the track, being greater than the distance between the raised position of the jack shoe and the lowered position of the jack head.

10. The method of building a fill and bodily moving a long portion of the track a considerable distance in excess of a mere track aligning movement laterally onto the new fill which comprises placing material at the side of the track until the top of the placed material is above the level of the bottom of the track rail and above the level of the track ties and engaging the ends of the track ties, then applying a moving and lifting pressure to the rail of the track which is adjacent the placed material to simultaneously shift the ties substantially in the direction of their length through the material and shift the track laterally over on the material while concomitantly laterally moving the top portions of the material by pushing such portions along by means of the rail and tie ends.

11. The method of building a fill and bodily moving a long portion of the track a considerable distance in excess of a mere track aligning movement laterally onto the new fill comprising placing material at the side of the track so as to build a mound close to the side of the track and extending higher than the top of the track rail, then concomitantly shifting the track bodily onto the placed material and spreading the top of the mound by means of the track itself and pushing the ends of the track ties through the said material by jacking the track laterally and at a small upward angle controlled to provide a desired height of the track and which slightly lifts the advancing side of the track as the track shifts laterally.

12. The method of building a fill and bodily moving a long portion of the track a considerable distance in excess of a mere track aligning

movement laterally onto the new fill comprising placing material at the side of the track so as to build a mound close to the side of the track and extending above the top of the ties and engaging the ends of the track ties, then jacking the rail laterally to force the ends of the ties through the placed material and forcing the top of the placed material along by means of the rail, then causing a second jacking operation with a second purchase on the rail but with the same jack footing.

13. The method of building a fill and bodily moving a long portion of the track a considerable distance in excess of a mere track aligning movement laterally onto the new fill which comprises transporting material over a track and dumping the material at one side of the track to form a mound parallel to the track length immediately adjacent the track and projecting above the level of the ties, then jacking the rail of the track which is adjacent the mound to shift the track rails and ties in a substantially horizontal direction through the material dumped and thereby move and spread the dumped material by the track and ties.

14. The method of building a fill and bodily moving a long portion of the track a considerable distance in excess of a mere track aligning movement laterally onto the new fill which comprises transporting material over a track and dumping the material at one side of the track to form a mound parallel to the track length immediately adjacent the track with the bottom of the mound below the level of the track and with the top of the mound projecting above the level of the ties, then jacking the rail of the track which is adjacent the mound to shift the track rails and ties in a substantially horizontal direction and thereby by level and spread the dumped material until 40 the ends of the ties are adjacent the edge of the fill.

15. The method of building a fill and bodily moving a long portion of the track a considerable distance in excess of a mere track aligning movement laterally onto the new fill which comprises transporting material over a track and dumping the material at one side of the track to form a mound parallel to the track length immediately adjacent the track and extending downwardly to a point below the level of the track and projecting above the level of the ties, then jacking the rail of the track which is adjacent the mound to shift the track rails and ties substantially horizontally thereby moving and spreading the dumped material by the track and ties, and concomitantly pushing a substantial portion of the material that is provided between the ties along with the adjacent material at the side of the track to maintain the ties of the track substantially on top of the fill.

16. The method of building a fill and bodily moving a long portion of the track a considerable distance in excess of a mere track aligning movement laterally onto the new fill which comprises transporting material over a track and dumping the material at one side of the track to form a mound parallel to the track length immediately adjacent the track with the bottom of the mound below the level of the track and with the top of the mound above the bottom of the ties and engaging the ends of the track ties, then jacking the rail which is adjacent the dumped material to apply a moving and lifting force at an inclination coordinated with the desired track height and thus shift the ties substantially in the direction of their length through the dumped material and laterally over on the material while concomitantly pushing portions of the material by the ends of the ties.

EDWARD O. KEATOR. 40
